UNITED STATES PATENT OFFICE.

ARTHUR WILFRED BREWTNALL, OF NEWCASTLE-UPON-TYNE, ENGLAND.

SURFACE HEATING OR COOLING APPARATUS.

No. 799,621.

Specification of Letters Patent.

Patented Sept. 12, 1905.

Application filed April 12, 1905. Serial No. 265,090.

To all whom it may concern:

Be it known that I, ARTHUR WILFRED BREWTNALL, a subject of the King of Great Britain, residing at Newcastle-upon-Tyne, England, have invented certain new and useful Improvements in Surface Heating or Cooling Apparatus, of which the following is a specification.

The present invention refers to that type of surface heating or cooling apparatus primarily composed of indented plates placed together surface to surface, so that the indented surfaces of one plate are in contact, or nearly so, with the adjacent plates, and in which, when the indentations are formed continuously—that is to say, when the plates are corrugated—the corrugations of one plate extend in a diverse direction to the corrugations of the next adjacent plate. In such a structure it is necessary to close the interspaces at the edges upon the two sides of the first pair of plates, leaving the interspaces at the edges upon the two ends of the first pair of plates open. The next chamber is formed between the external surface of one of the plates of the first chamber and the next adjacent plate, and in regard to this second chamber it is necessary to close the interspaces at the edges upon the two ends while the two opposite sides are left open. When this is done, one of the mediums—say steam—can be passed in one direction between a pair of plates, while the other medium—say cooling-water—can be passed between the outer surface of one of such plates and the next adjacent plate in an opposite direction, and so on, one medium thus passing through alternate chambers in an opposite direction to the other medium. In such apparatus it has been heretofore proposed to effect the complete closure of the interspaces by the insertion between such edges of a solid strip of metal or to effect such closure by running molten metal between the said edges. Those interspaces to be left open had inserted between them a bar, formed with serrations or the like, through which the medium was to pass to and from the interior of the apparatus.

Now the present invention primarily refers to an improved construction whereby those edges of the plates which are to be completely closed are brought into surface contact and held together by pressure, thereby dispensing with inserted solid bars or the running of molten metal between such edges and producing a joint of simple and perfect

character, while, on the other hand, those interspaces between the edges of the plates which are to be left open afford very easy entrance and exit for the passing medium. At the same time the construction according to the present invention permits of the plates being very readily separated one from another for the purpose of cleaning or repair.

An example of construction of apparatus according to this invention is illustrated in the accompanying drawings, whereon—

Figure 1 shows one of the plates employed in constructing such apparatus in vertical longitudinal section on the line X Y of Fig. 3. Fig. 2 is a similar section on the line X' Y' of Fig. 3—that is, at right angles to the section at Fig. 1; and Fig. 3 is a plan view of such a plate, central portions being broken away for economy of space. Fig. 4 shows a pair of such plates placed together to form a chamber according to this invention. Fig. 5 is a perspective view showing a corner portion of several of such chambers arranged in conjunction. Fig. 6 is an elevation showing a bunch of plates secured together, and Fig. 7 is a perspective view of one of the skeleton distance-pieces detached. Figs. 8 and 9 show an example of construction of a casing suitable for containing the bunches of chamber-forming plates, Fig. 8 being a half longitudinal section and half side elevation, and Fig. 9 is a plan view, the left-hand half of same showing the top cover removed.

According to this invention and referring to Figs. 1, 2, and 3, the corrugated or equivalent formations 1 in any plate (which is to form one of a series) are not allowed to extend to any of the edges of that plate, and therefore each plate presents plain margins at all its edges. Moreover, the plates are formed by pressing or stamping, so that the two opposite margins, or, as I will term them, two opposite "side margins" 2 3, are in a different but parallel plane to the plane of the end margins, the example in the drawings illustrating the side margins 2 3 formed flush with the apices of the corrugations on the upper surface of the plate, while the two opposite plain margins 4 5 at the ends of the plate are made flush with the apices of the corrugations on the under surface of the said plate. Each plate is of similar formation, and two of such plates are then placed surface to surface in contact, or nearly so, so as to bring two opposite side margins 2 3 of one plate into absolute surface contact with the two opposite side

margins of another similar plate, as is shown at Fig. 4 of the drawings, and then it will be found that the two opposite end margins of the plates will not be in contact, but will present free spaces for the passage of one of the 5 mediums—say a cooling medium—in between the corrugations of the two plates, which corrugations in the construction illustrated extend in diverse directions, being in contact 10 only at their crossing-points. Upon such a structure composed of two plates, as at Fig. 4, and forming one chamber I place a third plate of precisely similar construction to the plates described and so placed that its end 15 margins are in surface contact with the end margins of the plate upon which it is placed, leaving a space between the side margins of the latter plate and the said third plate for the passage of, say, the medium to be cooled. 20 Other plates are arranged one upon another until a bunch of plates of the requisite number have been so built up. A corner portion of several chambers so built up is illustrated in perspective at Fig. 5, from which 25 it will be understood that the two plates, which I have marked 6 7, forming one chamber, have their side margins 2 2 and 3 3 in absolute contact, while both the end margins 4 4 and 5 5 of the same plates are at a distance 30 from each other, so that fluid can pass in between the end margins of this chamber while the side margins are closed to the passage of the said fluid. The next chamber in the drawings at Fig. 5, below that formed by 35 the plates 6 7, is precisely similar in every respect; but by placing the two chambers so formed in surface contact, as shown, it will be seen that between the two chambers the intermediate chamber is formed, the sides 8 40 of which are open, while the ends are closed, and therefore the medium—say the medium to be cooled—will be free to pass in at the sides 8 of this intermediate chamber from one end to the other thereof, so that adjacent equal 45 and alternate chambers are formed for the two mediums—say steam to be condensed and cooling-water—the said mediums passing through those alternate chambers in opposite directions to each other. Such a structure is 50 fitted with solid distance-blocks 9, (see Figs. 5 and 6,) inserted between the corners, and these distance-blocks 9 may be attached to each plate separately by soldering, riveting, or other means before the plates are assembled, the said corner-blocks 9 being faced off to the proper level and serving when the plates are so assembled into a bunch to carry 55 the contacting margins continuously to the opposite edges of the plates. At the openings 60 to the respective chambers skeleton distance-pieces 10 are inserted which not only maintain the said openings uniform, but, as will be hereinafter seen, also serve the office of aiding in the clamping together of those margins of the plates which are in actual sur-

face contact with each other. These skeleton distance-pieces 10 may, as shown, be formed by a dent or crimped metal bar or strip or may consist of a serrated or pierced bar; but the said distance-pieces should be such as to 70 present large passage-ways 10^x and offer the least possible obstruction to the passage of the medium into and out of the chamber. The structure is then placed between two end clamping-plates, such as 11 12, Fig. 6, which 75 clamping-plates should be of sufficient strength and rigidity, and these two clamping-plates 11 12 are held together by bolts or by pressure-screws 13, as shown, and if found requisite the contacting margins of the plates 80 may have any suitable packing inserted between them, and the pressure applied by the clamping-plates forms a good and tight joint between the edges of the plates, while at the same time the plates composing the bunch may 85 be readily separated for cleaning or repair. Bunches of plates such as have been described with reference to Fig. 6 are then placed in any conveniently-constructed casing, so that one medium—say the medium to be 90 cooled—is passed into and through alternate chambers in one direction, while the other medium—say the cooling medium—is passed through alternate chambers in an opposite direction. In order to render the invention 95 capable of being easily carried into practice, a form of such a casing is shown by way of example at Figs. 8 and 9. This casing consists of a box-like body 14, into which six bunches 15 of the described plates are placed 100 and rest on internal flanges 16 of the casing. The body 14 of the casing upon each side is formed with a tubular communication, (see Fig. 9,) one such, marked 17, serving, for instance, as the inlet for the cooling-water when 105 the apparatus is used as a condenser, while the other communication, 18, serves for the outlet for the cooling-water, and in its passage the cooling-water entering by the channel 17 has free admittance to one edge of the 110 series of bunches of plates and passes through in between those alternate pairs of plates, finding its exit on the opposite side by the tubular communication 18. The top and bottom covers 19 20 of the casing 14 are formed 115 the one with an inlet by which steam to be condensed enters and the other with an exit. The steam has admittance to the top edge of the bunches of plates and passes between the alternate pairs of plates, finding its exit in the 120 bottom cover 20 by the exit-passage there provided after having been brought into very intimate proximity with the cooling medium, which passes, as before explained, in an opposite direction through the adjacent chambers. 125

What I claim as my invention, and desire to secure by Letters Patent, is—

1. In surface heating or cooling apparatus; the combination of a number of indented or corrugated plates of equal sizes, each plate 130

having a plain margin at all its edges, the plain margins at the sides thereof being in a different parallel plane to the plain margins at the ends of the same plate, a number of such plates being placed with their surfaces in contact, or nearly so, so that the plain margins at the sides of the first two plates are in surface contact, while the plain margins at the ends are separated, the next plate being placed so that its plain end margins are in surface contact with the plain end margins of the adjacent plate while its side margins are at a distance from the side margins of the adjacent plate, and so on, distance-blocks located at the corners between the plates, skeleton distance-pieces located between the separated edges of the plates, and means for clamping the collection of plates together to form fluid-tight joints between the contacting margins of the plates; whereby alternate chambers are formed for the passage in one direction of the cooling medium, while the medium to be cooled passes in an opposite direction through the remaining alternate chambers.

2. In surface heating or cooling apparatus; the combination of a number of indented or corrugated plates of equal size, each plate having a plain margin at all its edges, the plain margins at the sides thereof being in a different parallel plane to the plain margins at the ends of the same plate, a number of such plates being placed with their surfaces in contact or nearly so, so that the plain margins at the sides of the first two plates are in surface contact, while the plain margins at the ends are separated, the next plate being placed so that its plain end margins are in surface contact with the plain end margins of the adjacent plate, while its side margins are at a distance from the side margins of the adjacent plate, and so on, distance-blocks located at the corners between the plates, skeleton distance-pieces located between the separated edges of the plates, means for clamping the collection of plates together to form fluid-tight joints between the contacting margins of the plates, and means for directing the flow of one medium to be heated or cooled through one series of alternate chambers formed between the plates, and the opposite medium through the other adjacent alternate chambers.

3. In surface heating or cooling apparatus; the combination of a number of indented or corrugated plates of equal size, each plate having a plain margin at all its edges, the plain margins at the sides thereof being in a different parallel plane to the plain margins at the ends of the same plate, a number of such plates being placed with their surfaces in contact, or nearly so, so that the plain margins at the sides of the first two plates are in surface contact while the plain margins at the ends are separated, the next plate being placed so that its plain end margins are in surface

contact with the plain end margins of the adjacent plate while its side margins are at a distance from the side margins of the adjacent plate, and so on, distance-blocks located at the corners between the plates, skeleton distance-pieces located between the separated edges of the plates, a clamping-plate located on the outer surface of each end plate of a bunch, means for drawing together the clamping-plates to clamp the structure to form fluid-tight joints between the contacting margins of the plates, and means for directing the flow of one medium through one series of alternate chambers formed between the plates and the opposite medium through the other adjacent alternate chambers.

4. In surface heating or cooling apparatus; the combination of a number of corrugated plates of equal sizes superposed one upon another with the apices of the corrugations in contact and extending in diverse directions, a plain margin round all the edges of each plate, the plain margins at the sides thereof being in a different parallel plane to the plain margins at the ends of the same plate, a number of such plates being placed with their surfaces in contact as aforesaid so that the plain margins at the sides of the first two plates are in surface contact, while the plain margins at the ends are separated, the next plate being placed so that its plain end margins are in surface contact with the plain end margins of the adjacent plate, while its side margins are at a distance from the side margins of the adjacent plate and so on, distance-blocks located at the corners between the plates to continue the plain side margins to the ends of the plates, skeleton distance-pieces located between the separated edges of the plates, a clamping-plate located on the outer surface of each end plate of a bunch, means for drawing together the clamping-plates to clamp the structure together to form fluid-tight joints between the contacting margins of the plates, and means for directing the flow of one medium through one series of alternate chambers formed between the plates and the opposite medium through the other adjacent alternate chambers.

5. In surface heating or cooling apparatus; the combination of a number of indented or corrugated plates of equal size, each plate having a plain margin at all its edges, the plain margins at the sides thereof being in a different parallel plane to the plain margins at the ends of the same plate, a number of such plates being placed with their surfaces in contact, or nearly so, so that the plain margins at the sides of the first two plates are in surface contact while the plain margins at the ends are separated, the next plate being placed so that its plain end margins are in surface contact with the plain end margins of the adjacent plate while its side margins are at a distance from the side margins of the ad-

4
jacent plate, and so on, a distance-block fixed on one side and at each corner of each plate to two opposite plain margins thereof and faced off level with the other two opposite 5 margins to continue the latter plain margins to the ends of the plates, skeleton distance-pieces composed of a crimped metal strip located between the separated edges of the plates to hold the same at the proper distance apart, a 10 clamping-plate located on the outer surface of each end plate of a bunch, and pressure-screws for drawing together the clamping- plates to clamp the structure to form fluid-

tight joints between the contacting margins of the plates, a casing for containing such 15 bunches of plates, conduits to the casing for conducting one medium in one direction through the alternate chambers of the bunches, and conduits to the casing for conducting the other medium in an opposite direction through 20 the remaining alternate chambers of the bunches.
